BOAT PROPELLING MECHANISM

David G. Chandler and Robert T. Svendsen,
Minneapolis, Minn.

Application August 12, 1936, Serial No. 95,560

9 Claims. (Cl. 115—41)

Our invention relates to outboard propelling units for boats, and the primary object is to provide an efficient, practical, and comparatively simple and rugged design of drive unit assembly which is especially an improvement over the general type of mechanism as disclosed in the co-pending application Ser. No. 702,920, filed by Robert T. Svendsen (one of present applicants) for Boat propelling mechanism.

More particularly a further and more specific object is to provide the unit with an anti-cavitation plate which is disposed at an angle, forwardly inclined with respect to the horizontal, so as to best utilize the action of the water passing into the usual initial swell in the wake behind the boat, to hold the unit down in operative position and thus counteract the normal tendency of the propeller to lift forwardly out of the water. A further object is to incline the cavitation plate laterally to both sides from its median line, or as seen in cross section, whereby listing of the vessel, as when making a turn, will not cause one side of the plate to lift out of the water to thereby lessen or destroy its anti-cavitation function. A further object is to provide a novel and efficient method or means for manually adjusting and holding the drive unit at various elevations and for raising it to a completely inactive, vertical position for inspection, repair, or removal. A further object is to provide a novel arrangement of cooling means in conjunction with the drive unit assembly for cooling water circulated from the cooling system of the engine or motor that drives the propelling mechanism. These and still other more detailed and specific objects will be disclosed in the course of the following specification, reference being had to the accompanying drawing, wherein:

Fig. 1 is a left hand side elevation of our improved drive mechanism, as applied to the stern or transom wall of a boat, and with the major portion of the unit in sectional elevation for purpose of illustration.

Fig. 2 is a detail plan view of the lift lever retaining bar, as on line 2—2 in Fig. 1.

Fig. 3 is a transverse sectional elevation on line 3—3 in Fig. 1.

Fig. 4 is a detail elevation of a portion of the unit, as viewed from the right hand side.

Referring to the drawing more particularly and by reference characters, 5 designates the drive unit mounting plate, which is secured in and to the transom wall 6 of the boat 7, in the manner more fully disclosed in the aforesaid men-

tioned application Ser. No. 702,920. As in said application also the present plate 5 has an integral hub portion 8 serving as a bearing for a slightly inclined stub shaft 9 the rear or outer end of which is connected by a universal joint 10 to the propeller shaft 11 having the propeller 12. Thus power is transmitted from the inboard engine or motor (not shown) through parts 9, 10, and 11 to the propeller.

The propeller shaft 11 is mounted in upper and lower bearings, 13 and 14, in a cast frame or housing 15, the upper or forward end of which is bifurcated and pivotally secured, as at 16, to two transversely spaced lugs 17 extending integrally and rearwardly from the plate 5. The pivot center 16 is axially aligned with the center of universal joint 10 so that power can be transmitted freely while the frame 15 is vertically adjusted, and this condition also permits the frame to be swung upwardly to or beyond a vertical position for repair or inspection purposes.

The frame is vertically adjusted, within certain limits, by a hand lever 18 which pivots, as at 19, to a casting 20 to permit slight transverse adjustment of the lever and thereby facilitate engagement and release thereof with respect to spaced hooks or teeth 21 of an arm 22 extending rearwardly from and rigidly with respect to the plate 5. The casting 20 is mounted for oscillation on one of the pivot pins 16 and has a laterally projecting lug 23 for engaging under an edge of the frame to lift and support the latter. The lever arm 18 has freedom for only limited rearward movement, however, and consequently when it is desired to swing the frame up to its vertical and completely inactive position it is grasped by hand and pulled forward to thus disengage from the lug 23 and to swing independently of the members 18—20.

The frame 15 includes a long integral fin 24 which extends downwardly and rearwardly, terminating in a shoe 25 under the propeller 12. This fin, and its shoe, serve not only to reinforce the frame, but also serve as a propeller guard so that the propeller will not become damaged by striking against obstructions in the water. The shoe portion 25 further serves as a bearing support and guard for the lower end of the rudder, 26. The fin and shoe additionally serve the useful and important purpose of initially contacting submerged obstructions such as rocks and logs, and because of their particular form and position in the water will ride or pass over such obstructions, and when doing so will carry the pro-

steller and rudder up out of destructive contact with such obstructions or objects.

The upper end of the rudder 26 is journaled, as at 27, in a rearwardly extending, integral portion of the frame 15, which portion includes an anticavitation plate 28, and a central, vertically disposed reinforcing rib 29. The upper end of the rudder shaft has a bevel gear 30, which meshes with a gear segment 31 of a sleeve 32 journaled in a small bracket 33 pivoted to the rib 29, as at 34. A squared shaft 35 is slidable in the sleeve 32, and when rotated operates through the gear members 31-30 to angle the rudder in either direction to steer the vessel as may be desired. The sliding action of the shaft 35 in sleeve 32 permits of vertical fluctuations of the frame 15, while the boat is being operated, and also permits the complete raising of the frame to inactive position, without disrupting the operative association of the shaft with respect to the propeller. The upper end of the shaft 35 is turned by a suitable control device within the boat, operating through a horizontal shaft and a universal joint 36. The lower or rear end of the shaft 35 is provided with a resilient collar 37 which is adapted to abut against the sleeve 32 and thereby limits the downward movement of the frame 15 with respect to the boat and the water level.

30 We have provided means for lowering the temperature of the engine cooling fluid medium in the form of a chamber 38, arranged within or adjacent the housing 15. This chamber is connected by inlet and outlet conduits 39 which lead 35 to and through the plate 5 of the transom wall 6 and connect with the usual water circulation system of the power supplying engine. As the chamber 38 is subjected to the cooling action of the water on which the craft floats the engine 40 cooling medium is cooled without drawing lake water into the system which is objectionable because of the clogging which frequently occurs under such circumstances. It may be noted that the conduits 39 are flexible, at least in part, to 45 permit of the necessary vertical movements of the frame when swung on the axis 16.

Attention is now directed to the form, inclination, and other characteristics of the anticavitation plate 28, all of which constitute substantially important features of the present invention. It will first be noted that the plate slopes or inclines downwardly, or at a forward angle with respect to the horizontal, and that its forward end is disposed at a point or level below the 55 bottom of the stern end of the boat. The purpose of this arrangement is to cause the force of the water traveled through to exert a downward pressure on the frame 15, and which pressure will in turn counteract the normal tendency of 60 the propeller to lift the frame (and boat stern) out of the water. While so doing the plate 28 also of course operates in a known manner to prevent or effectively resist the water cavitating tendency of the propeller. In Fig. 1 of the drawing we have illustrated by dotted lines the general 65 contour of the water surface under varying conditions. Thus line A designates the normal horizontal water surface when the boat is at rest. Line B indicates the contour of the swell or wave 70 following in the wake of the boat when traveling at a medium or average speed; and line C indicates the more elongated swell as it occurs under relatively high speed conditions. Thus the 75 position and form of the swell with respect to the boat will depend upon the character and

speed of the boat, but in any event the forward angle of the anti-cavitation plate is such as to fully and properly utilize the (relative) water current to obtain the required downward pressure on the frame as the boat travels forwardly 5 under the action of the propeller.

It will be noted with particular reference to Fig. 3, that the plate 28 slopes laterally and to both sides from its median line attachment to the lower end of rib; and while the plate is here 10 shown as arcuate in cross section, substantially the same effect may be had by merely inclining two plane plate sections. In either event the object is to prevent the plate from laterally projecting above the water surface when the boat 15 is being turned, at which time the list of the boat has a tendency to transversely tilt the plate, and this in turn greatly reduces the anti-cavitating properties of the plate. But by angling or depressing the side edges of the plate the objection 20 thus caused by listing or tilting of the boat is largely overcome.

It is understood that suitable modifications may be made in the structure as disclosed, provided such modifications come within the spirit and scope of the appended claims. Having now 25 therefore fully illustrated and described our invention, what we claim to be new and desire to protect by Letters Patent is:

1. A propulsion apparatus for a boat having an 30 inboard motor, comprising an outboard frame normally disposed in an inclined position rearwardly of the boat and pivotally attached thereto so as to be swingable in a vertical plane parallel with the direction of travel, a propeller carried 35 by the rear end of the frame, drive connections extending from the propeller to the motor, a rudder carried by and angularly adjustable with respect to the frame, and an anticavitation plate carried by the frame above and forwardly of the 40 propeller, said plate when in normal operative position having its forward end disposed at a lower level than the rear end.

2. An outboard drive unit for a boat comprising a frame pivotally secured to and extending 45 rearwardly from the boat for vertical adjustment with respect thereto, a propeller shaft mounted in the frame and having a propeller secured upon the rear end thereof, the axis of said shaft and propeller being operatively disposed at an acute 50 angle with respect to the horizontal, and a plate carried by the frame for engagement in the water and disposed for operation at an angle normally sloping forwardly and downwardly whereby when the boat moves forwardly the 55 action of the water on the plate will produce a downward pressure on the frame to counteract the lifting tendency of the angularly disposed propeller and the impact of the water against the 60 housing.

3. An outboard drive unit for a boat comprising a propeller shaft extending at an angle downwardly and rearwardly from the rear of the boat, a propeller carried by the rear end of the shaft for rotation about the inclined axis thereof, means 65 for mounting the shaft permitting vertical fluctuations of the propeller end thereof, and a rearwardly and upwardly inclined plate associated with the mounting means for travel movement below the water surface and for converting the 70 relatively rearward water pressure to downward pressure to thereby counteract the normal tendency of the frame to rise.

4. An outboard drive unit for a boat comprising 75 a propeller shaft extending at an angle down-

wardly and rearwardly from the rear of the boat, a propeller carried by the rear end of the shaft for rotation about the inclined axis thereof, means for mounting the shaft permitting vertical fluctuations of the propeller end thereof, and a rearwardly and upwardly inclined plate associated with the mounting means for travel movement below the water surface and for converting the relatively rearward water pressure to downward pressure to thereby counteract the normal tendency of the mounting means to rise when the propeller is in motion, said plate being disposed above and forwardly of the propeller so as to serve as an anti-cavitation member with respect thereto.

5. An outboard drive unit for a boat having an inboard power plant, comprising a frame member pivotally attached at its forward end to the stern of the boat so that its other end may be moved vertically in a plane parallel with the direction of travel, a propeller and a rudder at the rear end of the frame, a rudder operating shaft disposed above and in general parallelism with the frame and having a sliding connection with the rear 10 end of the frame, said shaft having means forming a stop to limit the downward movement of the frame in the water.

6. An outboard drive unit for a boat having an inboard power plant, comprising a frame member pivotally attached at its forward end to the stern of the boat so that its other end may be moved vertically in a plane parallel with the direction of travel, a propeller and a rudder at the rear end of the frame, a rudder operating shaft disposed above and in general parallelism with the frame and having a sliding connection with the rear end of the frame, said shaft having means forming a stop to limit the downward movement of the frame in the water, and said

stop means being of a resilient character to cushion the supporting action of the shaft with respect to the frame.

7. An outboard drive unit for a boat, comprising an inclined frame member pivotally attached at its forward upper end to the stern end of the boat and having a propeller at its rear end for operation at a relatively lower level in the water back of the boat, and means for vertically adjusting the frame comprising a lever extending upwardly from the frame, and a toothed arm projecting rearwardly from the boat for releasable engagement by the lever.

8. An outboard drive unit for a boat, comprising an inclined frame member pivotally attached at its forward upper end to the stern end of the boat and having a propeller at its rear end for operation at a relatively lower level in the water back of the boat, and means for vertically adjusting the frame comprising a lever extending upwardly from the frame, and a toothed arm projecting rearwardly from the boat for releasable engagement by the lever, said lever having freedom for limited transverse movement.

9. An outboard drive unit for a boat, comprising an inclined frame member pivotally attached at its forward upper end to the stern end of the boat and having a propeller at its rear end for operation in the water back of the boat, and means for vertically adjusting the frame comprising a lever extending upwardly from the rear end of the frame, and a toothed arm projecting rearwardly from the boat for releasable engagement by the lever, said frame being disengagable with respect to the lever whereby the frame may be swung upwardly and forwardly beyond the position of lifting limit of the lever.
